Inventor:

Holmes Marshall,

By his Attorneys,

Thurston R. Baker

UNITED STATES PATENT OFFICE.

HOLMES MARSHALL, OF NEW YORK, N. Y.

ATTACHMENT FOR TYPE-WRITERS.

SPECIFICATION forming part of Letters Patent No. 749,312, dated January 12, 1904.

Application filed August 13, 1902. Serial No. 119,481. (No model.)

To all whom it may concern:

Be it known that I, HOLMES MARSHALL, a citizen of the United States, residing at New York, in the county of New York and State of New York, have invented a certain new and useful Improvement in Attachments for Type-Writers, of which the following is a full, clear, and exact description, reference being had to the accompanying drawings.

10 The object of this invention is to provide in very simple and efficient form devices adapted to be attached to a type-writer for temporarily stopping the carriage at any desired point, allowing the carriage to thereafter proceed on its course. The invention is thus of a special value in tabulating work, where it is desired after matter has been written to skip a distance and then begin figures in a certain column.

20 A more specific object of the invention is to provide the stopping devices in a form readily and conveniently adapted for attachment to an ordinary type-writer of the Remington style.

The invention may be best summarized as 25 consisting of the combinations and parts to the above ends, as hereinafter more fully explained, and definitely set out in the claims.

The drawings clearly show my invention as applied to a Remington type-writer.

30 Figure 1 is a plan of the upper portion of such type-writer. Fig. 2 is an end view, partly in section, of such portion. Fig. 3 is a face view of the escapement wheel and bar. Fig. 4 is a perspective view of one member of my stopping device. Figs. 5 and 6 are views of the other member of my stopping device in place 35 on the marginal stop-bar of the type-writer, Fig. 5 being a section on the line 5-5 of Fig. 2 and Fig. 6 being a front elevation.

40 Referring to the parts by letters, A represents the frame of the type-writer.

B is the front portion of the traveling carriage carrying the platen B' and pivoted to a rear portion C, which has rollers c, bearing 45 on a rod a, carried by the frame, and has a guiding-arm c', taking around a rod a', carried by the frame. Pivoted to the portion C of the carriage at d are arms d', to the front edge of which is secured the escapement-bar 50 D. This bar meshes with teeth on the escape-

ment-wheel E on the forward end of the shaft e, journaled in the housing e' and having at its rear end a wheel e', with which the escapement-dogs (not shown) may be operated. The carriage is given a tendency to move to the left by the strap H, taken around a spring-drum. (Not shown.) To allow the carriage to be shifted, there is pivoted to the portion B at f the lever F, whose rear end f' takes beneath an extension of the escapement-bar D, 60 wherefore when the forward end of this lever is depressed the escapement-bar is raised out of engagement with the wheel E, and the carriage may move to the left under the influence of the pull on the strap H. 65

Projecting rearward from the escapement-bar D on the ordinary Remington machine is a bar D², which is adapted to coöperate with marginal stops carried by the stop-bar G, supported by the frame. These marginal stops 70 are not shown. In use they are adjustable along the bar G and form a positive stop to the carriage by the engagement of the bar d², whether the escapement-bar D is in engagement with its pinion E or not. 75

The construction above set out is of the ordinary Remington form and is described thus fully simply for clearness in explaining the operation of my stopping device, which will now be described. 80

On the marginal stop-bar G of the type-writer I place a stop J, and on the arm d' I secure an extension K. This extension extends over the bar G and when the escapement-bar D is in engagement with the pinion E stands 85 high enough above the bar G to clear the stop J. This clearance of the stop when the escapement is in engagement is one of the features of this invention wherein it differs from the marginal stops heretofore employed, and 90 it is this clearance which allows my operation, for when the escapement-bar is raised to allow the carriage to be shifted the extension-arm K engages the stop J and stops the carriage; but as soon as the escapement-bar is thereafter lowered, coming into engagement with its pinion, the arm K is raised sufficiently to pass over the stop J, so that the type-writing may be continued. 95

The stop J consists in its preferred form 100

of a small sheet-metal plate bent into a **U** shape, having bent upward from its intermediate portion the lip j^3 and having bent inward from its rear portion the tooth j^2 , the rear portion being bent outwardly at j' , where there is pivoted the latch j^4 , adapted to take into a notch from the depending portion j on the front side of the stop. The stop is readily removable by turning the bar j^4 a quarter of the way back and may thus be placed in any position desired, and when so placed it is readily held by the tooth j^2 , engaging the notches on the rear side of the margin-bar G , while the latch-bar j^4 holds the stop snugly down onto the bar G .

The extension-arm K is formed of a sheet-metal plate bent over into the flat tubular form shown in Fig. 4. This form provides a tapered horizontal opening k , which the flat portion of the arm d^2 may occupy, while along the side of this is a downward opening k^3 , through which the downward projection on the arm d^2 may pass. The extension K has a projection k^2 , adapted to stand above the margin-bar G . Taking into the extension K are a pair of set-screws k' , which clamp it to the arm d^2 . This extension is thus readily removable, but is easily put in place, being slipped over and clamped to the peculiarly-shaped arm d^2 , having a downwardly-extending lip, such as is common on type-writers of the Remington type, and requiring no alterations whatever of such arm to carry the extension.

35 In using my stops the stop J is placed on the margin-bar (which has a scale upon it) at the position corresponding to that on the paper where the column is to begin. Then after the matter preceding the figures has been 40 written the lever F is depressed and the carriage shifted to the left until the arm K engages the stop J . Then the hand is taken off the lever F and the carriage is in position to begin the column-work.

45 Having described my invention, I claim—
1. In a type-writer, the combination of a frame, a bar carried thereby, a stop mounted on said bar, a carriage mounted to travel along the frame, a pivoted escapement-bar mounted 50 on the carriage, an escapement carried by the frame for engaging said escapement-bar, an arm extending rearward from said escapement-bar in a position to pass over the stop when the escapement-bar is in engagement but 55 to engage the stop when the escapement-bar is out of engagement, substantially as described.

2. In a type-writer, the combination of a frame, a stop-bar carried thereby, a carriage 60 mounted to travel along the frame, a pivoted escapement-bar mounted on the carriage, an escapement carried by the frame and adapted to engage said escapement-bar, an arm extending rearward from said escapement-bar to a 65 position directly over said stop-bar and some

distance above the bar, and a stop carried by said stop-bar and having a lip extending upward from the upper surface of the bar, the upper end of the lip being out of the path of the arm when the escapement-bar is in engagement but being in such path when the escapement-bar is out of engagement, substantially as described. 70

3. In a type-writer, the combination of a frame, a bar carried thereby, a stop mounted 75 on said bar, a carriage mounted to travel along the frame, a pivoted escapement-bar on the carriage, an escapement carried by the frame for engaging said escapement-bar, an arm extending rearward from said escapement-bar, 80 an extension-arm removably carried by the aforesaid arm in a position to engage the stop when the escapement-bar is out of engagement, and means for securing said extension-arm in place, substantially as described. 85

4. A stop for a type-writer consisting of a **U**-shaped plate having an upwardly-extending lug, an inwardly-extending tooth, and a latch-bar pivoted to one leg of the **U** and adapted to engage the other leg, substantially as de- 90

5. The combination with a notched bar of a type-writer of a stop made by a **U**-shaped plate, having an inwardly-extending tooth and having one of its legs turned outward, and a latch-bar pivoted to said outward extension and adapted to occupy a notch in the other leg. 95

6. A stop for a type-writer consisting of a **U**-shaped plate having the edge of its intermediate portion turned upward to make a lip j^3 and 100 having the edge of one of its legs turned inward to make an internal tooth j^2 , and having the lower portion of said leg turned outward as at j' , and a latch-bar j^4 pivoted to this outward extension and adapted to occupy a notch 105 in the other leg j which depends below the latch-bar, substantially as described.

7. The combination with a type-writer having an extending arm with a projecting lip, of an extension made tubular and adapted to slide 110 over said arm, and means for rigidly securing said extension thereto, substantially as described.

8. The combination with a type-writer having an extending arm with a downwardly-turned lip, and an extension made tubular and provided with an opening on its under side near one edge to allow the passage of said lip whereby the extension may be slid over said arm, substantially as described. 115

9. The combination with a type-writer having an operating-arm, of an extension thereof consisting of a body-plate, a downwardly-projecting wing at an angle thereto, said body-plate being bent backward upon itself so as to form a flattened tubular portion, said bent-back portion being on the under side of the body-plate, and means for holding said extension to said arm, substantially as described. 125

10. An extension-arm for a type-writer con- 130

sisting of a plate K bent onto itself to form a tubular portion k , with an opening k^3 , said extension-arm having a projecting wing k^2 , and a screw carried by said tubular portion k for 5 clamping it rigidly in position, substantially as described.

11. An extension-arm for a type-writer, consisting of a plate K bent onto itself to form a flat tubular portion k with a longitudinal opening k^3 upon its under side near one edge, said 10

extension-arm having a wing k^2 formed by turning downward the free edge along the side of said opening, substantially as described.

In testimony whereof I hereunto affix my signature in the presence of two witnesses. 15

HOLMES MARSHALL.
